Clark Mills Charleston, South Carolina.
Letters Patent (Design No 38) Dated 7th October 1845

The schedule referred to in these Letters Patent and making part of the same.

To all whom it may concern. Be it known that I, Clark Mills of the City of Charleston, in the District of Charleston and State of South Carolina have produced a new design of a Bust of the Honble John C. Calhoun of South Carolina and late Secretary of State of the United States Government and hereby declare that the following is a full and accurate description of the same.—

The Bust is Plaster of Paris (or other material) uncolored and from the Crown of the Head to the Collar bone an exact cast in every particular of the living representation aforesaid. The Head and neck resting upon an ordinary pedestal of the same material as per drawing herewith accompanying.

And I hereby declare that I am the original producer of the said Bust, of the Honble John C. Calhoun aforesaid and that I claim to obtain an exclusive property or right therein, to manufacture, sell and vend the same or copies of the same to others or by them to be made & sold.
